(57) **CLAIM**

The ornamental design for a combined beverage mug and can holder, as shown and described.

DESCRIPTION

FIG. 1 is an assembled front perspective view of the combined beverage mug and can holder, with a removable cup portion shown inserted in the holder and with a beverage can shown in broken lining;

FIG. 2 is a left side elevation view;

FIG. 3 is a top plan view;

FIG. 4 is a rear elevation view;

FIG. 5 is a left side elevation view;

FIG. 6 is a bottom plan view;

FIG. 7 is a front elevation view; and,

FIG. 8 is an exploded view, corresponding to FIG. 1, with the removable cup portion shown removed from the holder.
